Application January 2, 1942, Serial No. 425,459

1 Claim. (Cl. 215—83)

This invention relates to new and useful improvements in closures especially adapted for those types of receptacles known as thermos bottles.

The principal object of the present invention is to provide a closure for thermos bottles which includes a stopper which cannot become displaced, which accidents frequently happen, perhaps with the ruination of an adjacent lunch.

Other objects and advantages of the invention will become apparent to the reader of the following description.

In the drawings:

Figure 1 represents a side elevational view of a thermos bottle showing the closure in place and the drinking cup cap in section.

Figure 2 is a section on the line 2—2 of Figure 1.

Figure 3 is a fragmentary side elevational view showing the stopper and carrier therefor removed from the neck.

Figure 4 is a bottom plan view of the stopper and carrier.

Figure 5 is a vertical sectional view through the stopper and carrier.

Figure 6 is a perspective view of the stopper carrier.

Referring to the drawings wherein like numerals designate like parts, it can be seen that numeral 5 generally refers to a thermos bottle which has a conventional neck portion 6, at the shoulder portion of which are threads 7.

In carrying out the present invention, a drinking cup cap 8 is employed which may be of conventional construction but of a size which will accommodate the present invention.

The present invention is more particularly and generally referred to by a numeral 9, the same comprising an internally and externally threaded

ring 10 having a cage-like construction defined by a pair of U-shaped members 11 and 12 crossed at their intermediate portions and to these crossed portions of the U-shaped members 11 and 12 is secured a stopper 13 by a rivet 14. This rivet passing longitudinally through the stopper 13 and through the crossed portions of the U-shaped members 11, 12.

The ends of the U-shaped members 11 and 12 are welded or otherwise secured to the upper side of the ring 10.

It can now be seen that by placing the ring 10 over the threaded portion 7 of the neck 6 and screwing the same down onto the neck, the cork or stopper 13 is driven into the neck 6 of the bottle and cannot become accidentally displaced without unscrewing the ring 10. The drinking cup cap 8 can then be disposed over the cage 11, 12 and the neck 6 and screwed onto the ring 10.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:

30 A closure for a bottle of the type provided with an upstanding tapering neck and external threads at the base of the neck, said closure including an annular internally threaded ring for turning onto said threads, a cage surmounting said ring and comprising a pair of U-shaped members upstanding from the ring in relatively right angled planes and including intersecting intermediate portions, and a stopper in said cage fixed directly to said portions at the intersection thereof.

ROBERT B. MARTIN.
